UNITED STATES PATENT OFFICE.

CHARLES H. LEONARD AND LARS H. SOLOSTH, OF GRAND RAPIDS,
MICHIGAN; SAID SOLOSTH ASSIGNOR TO SAID LEONARD.

KNOCKDOWN REFRIGERATOR.

SPECIFICATION forming part of Letters Patent No. 618,474, dated January 31, 1899.

Application filed November 22, 1897. Serial No. 659,408. (No model.)

To all whom it may concern:

Be it known that we, CHARLES H. LEONARD and LARS H. SOLOSTH, citizens of the United States, residing at Grand Rapids, in the county 5 of Kent and State of Michigan, have invented certain new and useful Improvements in Knockdown Refrigerators; and we do hereby declare the following to be a full, clear, and exact description of the invention, such as 10 will enable others skilled in the art to which it appertains to make and use the same.

Our invention relates to improvements in knockdown refrigerators; and its object is to provide a device that can be readily taken 15 apart and cleaned, shipped, or stored, and to provide the same with certain other new and useful features hereinafter more fully described, and particularly pointed out in the claims, reference being had to the accompanying drawings, in which—

Figure 1 is a transverse vertical section on the line 1 1 of Fig. 2; Fig. 2, a horizontal section on the line 2 2 of Fig. 1; Fig. 3, a perspective detail of a folding shelf; Fig. 4, a 25 perspective detail of one of the connecting-wires of said shelf; Fig. 5, an enlarged detail perspective of one corner of the ice-chamber lining; Fig. 6, a detail showing the detachable fastening for the drip-pipe, and Fig. 7 30 an enlarged detail of the lower angle of the ice-box lining.

Like letters refer to like parts in all of the figures.

A A represent the ends of the case, and B B 35 the front and back, respectively, of the same. The front and back overlap the edges of the ends and are secured thereto with suitable screws C or other detachable fastenings. At the top of the case is a suitable frame D, detachably secured by like fastenings E, upon which frame the top or cover F is supported. The bottom G is detachably held in place upon cleats H H and provided with a lining I, having an upturned edge I', extending upward back of the lower edges of the lining of the ends, front, and back, which latter have 45 their lower edges folded, so as to extend downwardly inside of the upturned edge of the bottom lining, thence over the top of said edge, and thence down outside of the same, where-

by said bottom and side linings are detachably interlocked, as shown at I" in Fig. 1.

J represents the bottom of the ice-chamber, having suitable openings for the air-currents and detachably supported on cleats K, attached to the front and back of the case.

L is the bottom lining of the ice-chamber, resting on the bottom J and having its edges L upturned all around and folded at the corners, as at L", and also provided with a central opening R for the escape of cold air and a rear opening S for the escape of water into the drip-pipe T. The ends of the ice-chamber are formed of plates M M, which plates are located at a distance from the ends of the case by means of strips Q in the respective angles of the case, thus forming the uptake-flues U U. Said plates are folded at their respective ends, first at right angles and then two return bends, thus stiffening the plates 70 and also forming vertical grooves at each end, in which are detachably inserted the edges of the front and rear lining-plates N. The lower edges of the plates M M N N all rest in the angles of the bottom lining L, and said 75 plates are bent outward slightly at their lower edges to form a space between their outer surface and the upturned edges L to prevent water from rising between the same by capillary attraction. The bottom, ends, and sides 80 of the ice-chamber are thus securely held in place and separately removable without any special fastenings or the use of solder or rivets and at the same time are sufficiently tight to properly direct the water and the air-currents.

The drip-pipe T is detachably held in place by means of a downwardly-extended strip v, of flexible material, having a recess W and folded upon itself, forming a spring-arm X. 90 Said strip is engaged with a staple Y in the back of the case, said staple entering the recess W and held therein by the outward pressure of the spring-arm X and detachable therefrom by pressing the pipe T backward 95 and upward.

The folding shelf consists of strips O, of sheet metal, turned in tubular form at their respective edges to stiffen them and also to receive the connecting-wires P, which wires 100

- turn freely in said tubular sides and are bent twice at right angles, forming lateral extensions P' equal in length to the space between the axes of the tubular sides of the 5 strips and portions parallel to the part P to engage the tubular edges of the adjacent strips. The strips are thus foldable one upon the other to reduce the width of the shelf when in use to permit a tall article to extend 10 above the same in the event said article should be too high to go between the shelves or for packing and storage. Said shelves are supported upon ledges P''' , formed in the end linings by folding the same inwardly at 15 right angles, and thence downwardly and outwardly at an acute angle, and thence downward at an acute angle, as shown in Fig. 1.
- By the described construction we avoid all use of solder, which does not hold well on galvanized iron. We are also able to remove all 20 the various shelves, the drip-pipe, and the sides and bottom lining of the ice-chamber and to separate the same into detached parts for storage or cleaning, and by removal of a 25 few screws or other suitable fastenings the outer case can be separated into the respective ends, front, back, top, and bottom, and thus readily cleaned or packed and shipped or stored in small compass.
- 30 Having thus fully described our invention, what we claim, and wish to secure by Letters Patent, is—
1. In a refrigerator a detachable ice-box lining consisting of a removable bottom in combination with two end plates and two side plates, each plate being independently removable, and supported in place by engagement at its ends with two of the other plates substantially as described.
  2. In a refrigerator, a detachable lining consisting of ends folded at each side to form vertical grooves, sides having their edges engaging said grooves, and a bottom having upturned edges embracing said sides and ends, 45 substantially as described.
  3. In a refrigerator, a detachable ice-chamber lining, consisting of a bottom having an opening for escape of cold air, and an opening for escape of water, an upturned outer edge, and folded corners; end plates folded at each side, once at right angles and twice with return folds, and sides having their edges engaging said folds, substantially as described.
  4. In a refrigerator, vertical strips in each corner, a removable bottom to the ice-chamber having central and side openings for air-currents, a bottom lining having a central opening for escape of cold air, and a rear 55 opening for escape of water, and upturned edges, folded at the corners, ends having right-angle and return bends at their sides, sides having edges engaging said ends, said ends and sides resting in the angles of the bottom lining and bent outward at their lower edges, 60 substantially as described.
  5. In a refrigerator, in combination with a case, and a removable drip-pipe, a staple in the case, and a downwardly-extended flexible strip attached to said pipe and having a recess to engage said staple, and a flexible arm engaging the case and yieldingly holding 65 said staple in said recess, substantially as described.
  6. In a refrigerator, a shelf consisting of strips of sheet metal having tubular edges, and connecting-wires inserted in said tubular edges and turning freely therein, substantially as described.
  7. In a refrigerator, a folding shelf consisting of strips having tubular edges, and wires in said tubular edges turning freely therein, said wires being bent twice at right angles near the ends of said strips and having lateral portions between said bends, substantially as 80 described.
  8. In a refrigerator, in combination with detachable sides and bottom, a bottom lining having upturned edges, and side linings folded at their lower edges to extend upward adjacent to said upturned edge, thence over the same, and thence downward upon the outside of the same, whereby said bottom and side linings are detachably interlocked, substantially as described.
  9. A knockdown refrigerator consisting of two ends, a front, a back, a top frame and cover, and a bottom, all detachably secured to each other and forming a case, a detachable drip-pipe, detachable shelves, and an ice-box bottom, and an ice-box lining consisting of a bottom lining having upturned edges, and two end plates and two side plates, two of which plates have folded edges forming grooves engaged by the edges of the other two plates, substantially as described.
  10. A knockdown refrigerator consisting of two ends, a front, and a back detachably secured to each other and forming a case, a drip-pipe, a bottom, shelves, and ice-box bottom, detachably supported within said case, a top frame supporting the cover and detachably secured in place, a bottom lining and side linings, said bottom lining having folded edges forming grooves detachably engaging the lower folded edges of the side linings, an ice-box lining consisting of a bottom lining having upturned edges, and ends having right-angle and return folds forming grooves, and side plates having edges detachably engaging 105 said grooves, said ends and sides having their lower edges bent outward and resting in the angles of the bottom lining, substantially as described.

In testimony whereof we affix our signatures in presence of two witnesses.
